UNITED STATES PATENT OFFICE

2,462,590

CAN-MARKING DEVICE

John Albertoli, San Francisco, Calif.

Application January 21, 1946, Serial No. 642,489

1 Claim. (Cl. 101—37)

This invention relates to improvements in means for marking cans, and particularly that type of cans used for packing sardines, anchovies and the like, which cans are relatively shallow and may be either oval or oblong in shape.

The principal object of this invention is to provide means whereby each can, as it passes down one of several delivery chutes, will receive a mark on one side thereof, which mark will designate the person packing at any one particular chute; this marking may be either the name of the person, a code or a number.

A further object is to produce a marking device which may be attached to and become a part of any of the standard makes of canning equipment such as shown in my co-pending application Serial No. 642,488, filed January 21, 1946.

A further object is to produce a device which is economical to install and one wherein changes may be made in the indicia on the code-wheel whenever the operator at that particular chute is changed.

Other objects and advantages will be apparent during the course of the following description.

In the accompanying drawings forming a part of this specification and in which like numerals are employed to designate like parts throughout the same,

Fig. 1 is a fragmentary detailed view showing the upper end of a delivery chute with my invention attached thereto, and

Fig. 2 is a cross-sectional view taken on the line 2—2 of Fig. 1, and looking from the left of the drawing and with the cans eliminated.

In the canning of fish, it is necessary for each packer to pick up a fish, remove the entrails, and to then place the fish in an empty can. When the can has been filled the same is removed and another can placed in its stead for the purpose of filling it.

It sometimes occurs that an operator may neglect to properly clean the fish, that is by removing the entrails, and as a result such cans are rejected by the inspectors; consequently, the entire shipment may be condemned.

It is, therefore, imperative that some means be provided for determining the identity of packers thus neglecting their work and in order to do so, it is necessary that each can be marked in some way.

For this purpose I have provided a marking device which may be attached to any standard canning equipment, so that each can, as it passes down the chute to the packer, will have an iden-

tification mark stamped thereon, thus enabling the inspector to determine immediately the name of the packer of the can which has been found to be defective. It has been proven that by the use of this device rejects have practically been eliminated.

In the accompanying drawings wherein for the purpose of illustration is shown a preferred embodiment of my invention, the numeral 5 designates the frame of an ordinary canning machine, upon which are mounted conveyor belts 6 and 7 positioned on opposite sides of the upper end of a chute 8. The bolts 6 and 7 are trained over pulleys 17 and 18 which are fixed on shafts 19 and 20. On each of the shafts is fixed a sprocket 21, these sprockets being driven by a chain 22.

As the cans A are moved by the conveyor 6 toward the conveyor 7, they will move into the broken line position B and down into the chute 20 8, if there is room within the chute for additional cans.

If the chute is full, then the cans will move from the position B to the dotted-line position C; thence, to position D and on toward the next chute.

The bottom can E in the chute comes to rest against stops 9, which are so positioned that when the chute is full of cans the uppermost can is at a point where its lowermost end is in the same plane as the axis of the marker-wheel 11, and the upper end of the can will act as a bridge to guide other cans from the belt 6 to the belt 7. The stops 9 at the bottom of the chute serve to position the bottom can into a convenient location for the operator to remove the can from the chute, after which another can may enter the top of the chute.

As these cans are oval in shape, it is apparent that the marker-wheel carrying indicia, stamping projections 10 lies within a vacant area formed by the contacting curved ends of the two uppermost cans in the chute.

This marker-wheel is rotated by gears 12 and 13, the gear 13 being fixed on one of the shafts 19 and the gear 12 meshing with the gear 13. The gear 12 is fixed on the rotatably mounted shaft 23 on which the marker-wheel 11 is also fixed. In order to permit the wheel 11 to enter the chute 8 a window 24 is provided in said chute.

A backing-wheel 14 serves to hold the can against the marking-wheel as the can passes downwardly through the chute.

An inking-pad is shown at 16, which rotates against the indicia projections 10.

It is, of course, understood that there may be

a large number of chutes extending along the packing area, each having a marking device.

The result of this construction is that as the cans move from the position A into the chute, they will pass downwardly and each can will be caused to move between the backing-wheel 14 and the marker-wheel 11, so as to cause a stamping on the side of the can, thereby identifying all cans passing through that particular chute.

It will thus be seen that I have produced a device which will accomplish all of the objects above set forth.

It is to be understood that the form of my invention herewith shown and described is to be taken as a preferred example of the same and that various changes relative to the material, size, shape and arrangement of parts may be resorted to without departing from the spirit of the invention or the scope of the subjoined claim.

Having thus described my invention, I claim:

In a machine for marking a side of a can, a vertical chute for said cans and having a window in one side, means for feeding cans into said chute, a belt pulley at the upper end of the chute adjacent the window provided side, a shaft whereon said pulley is fixed, a second belt pulley spaced from the first pulley, a belt trained around said belt pulleys for supporting on its upper run

cans overrunning the chute when filled, a shaft whereon said second pulley is fixed, driving means for said first shaft, a marker-wheel having a segmental portion projecting into the chute through said window, a rotatable shaft whereon said marker-wheel is fixed, gearing connecting said first and third shafts and moving the surface of the marker-wheel in synchronism with said belt, and stops at the lower end of said chute positioned to cause the column of cans in the chute to be held so that abutting ends of two adjacent cans in the chute lie opposite and free from said marker-wheel.
